FLAG AND JARDINIERE HOLDER
John J. St. Lawrence and Alice L. McMahon, both of
435 Essex St., Lynn, Mass. 01902
Filed May 5, 1966, Ser. No. 547,928
1 Claim. (Cl. 248—27.8)

This invention relates to the broad class of holders, and more particularly to holders for flags and jardinières, the holders being especially adapted to securement to tombstones.

Many people who like to place a flag at the grave of their loved-ones as well as flowers, find that neither the flag nor the flowers will remain very long in an upright position, no matter how much care is spent or what device is used to keep them in a vertical position.

It is, therefore, the principal object of this invention to provide a flag and jardinière holder that is especially adapted to hold a flag vertically upward on one side of a tombstone and a jardinière on the other side of the stone, a jardinière being a French name that is broadly interpreted to mean "flowerpot."

Another object of this invention is to provide a flag and jardinière holder of the character described comprising a strip of metal that is formed into the configuration shown in the accompanying drawing for securement to the upper end of a tombstone.

Still another object of this invention is to provide a flag and jardinière holder of the character herein described that will firmly hold both a flag on one narrow side of the tombstone and a jardinière on the other narrow side. The device will not distract one's attention from the tombstone to which it is secured as it is a thin strip of metal or the like that will not distract one's attention from the wording on the tombstone.

Other and further objects of this invention will become apparent as the description of the invention proceeds and the accompanying drawing is examined.

In the drawing:

FIGURE 1 is a front view of this invention secured to a tombstone which is shown in phantom lines.

FIGURE 2 is a pictorial view of this invention in its entirety.

FIGURE 3 is a top view of this invention.

FIGURE 4 is a pictorial view of a trio of tombstones showing this invention secured to each tombstone and supporting both a flag and jardinière on the narrow side of each tombstone.

In the drawing, like parts are indicated by like numbers. The number 10 indicates this entire invention which consists of an elongated U-shaped member 11 that is formed from a strip of metal or the like having two outwardly turned ends 12 through which passes the spring-loaded bolt 13. A vertically disposed tubular flag staff holder 14 is welded or otherwise secured to the lateral center of the end portion 15 of the aforesaid elongated U-shaped member 11 of this invention of ours.

To the other end 16 is welded or otherwise secured a

2

second U-shaped member 17 which holds the circular band 18 in which the jardinière is placed as one can understand by looking at FIGURES 1 and 2 of the accompanying drawing. A vertically disposed nameplate holder 5 19 is suitably secured to the aforesaid invention although the nameplate itself is not shown in any of the views of the accompanying drawing. The aforesaid tubular flagstaff holder 14 may be tapered slightly inwards towards the bottom 20 in order to prevent the flagstaff from slipping too far down in the holder or it may be replaced with a ring if so desired.

The way in which this invention of ours is used is so obvious from examination of the drawing as to need no explanation in this specification.

While this invention is preferably made from non-magnetic stainless steel, it can be made of any desired material. Changes and modifications may be made in the design and construction of the invention in so long as the changes and modifications fall within the scope and intent of the appended claim.

What we claim as new is:

A flag and jardinière holder adapted to be secured to the upper portion of a tombstone at a distance above the base portion thereof comprising, in combination, a first 25 relatively flat strip of material having a width substantially greater than its thickness, said strip being formed into a rectangular configuration for positioning around the upper portion of a tombstone and having end portions adjacent each other when so formed, said end portions 30 being turned outwardly from the plane of said strip substantially at right angles thereto to form a pair of ears, locking means for drawing said ears towards each other under tension whereby said strip may be tightly fitted to said tombstone, a circular band of material securely attached to one leg of said rectangle and positioned in the plane of said rectangle for holding a jardinière, and means forming a tubular fitting attached to an opposite 35 end of said rectangle and extending downwardly perpendicular to the plane of said rectangle whereby a flag staff may be supported in an upright position by said fitting.
